UNITED STATES PATENT OFFICE.

WARREN T. HEAPS AND WILLIAM THACKERAY, OF KEWANEE, ILLINOIS.

HEATER.

1,189,104.

Specification of Letters Patent. Patented June 27, 1916.

Application filed March 3, 1916. Serial No. 81,967

To all whom it may concern:

Be it known that we, WARREN T. HEAPS and WILLIAM THACKERAY, citizens of the United States, residing at Kewanee, in the county of Henry and State of Illinois, have invented new and useful Improvements in Heaters, of which the following is a specification.

This invention relates to improvements in heating devices and has particular application to a liquid fuel burning submersible heater.

In carrying out the present invention, it is our purpose to provide a heater of the class described which may be submerged in a tank of water or other liquid to heat the same and wherein the supply of fuel to the burner may be regulated so as to accelerate or retard the heating of the water or other liquid, and wherein the products of combustion may be carried off to the outer atmosphere, all of the heat units being extracted from the products of combustion as the latter pass to the atmosphere, thereby enabling the water to be heated in a comparatively short time and with a minimum consumption of fuel.

With the above and other objects in view, the invention consists in the construction, combination and arrangement of parts hereinafter set forth in and falling within the scope of the claim.

In the accompanying drawings; Figure, 1 is a view in elevation of a heater constructed in accordance with our present invention, the same being shown as immersed in a tank of water. Fig. 2 is a vertical sectional view through the heater. Fig. 3 is a cross sectional view on the line 3—3 of Fig. 2. Fig. 4 is a cross sectional view on the line 4—4 of Fig. 2.

Referring now to the drawings in detail, 1 designates a rectangular casing adapted to be placed in a tank containing water or other liquid to be heated and having the top wall thereof formed adjacent to the end walls of the casing with openings 2 and uprising from the top wall concentrically of the openings 2 respectively are flues 3 of a height sufficient to project above the water line of the receptacle in which the tank is arranged. Secured to the upper ends of the flues 3 are hoods 4 spaced apart from the upper edges of the flues to form an air space between the hoods and the flues.

These hoods serve to prevent the entrance of rain, etc., to the flues, but permit the passage of air through the flues. The central portion of the top wall of the rectangular casing 1 is concavo-convex as at 5 and arranged beneath the concavo-convex portion of the top wall of the casing is a burner 6 and arranged immediately above the burner 6 between the latter and the portion 5 is a perforated grate 7 designed to break up the blaze from the burner, while encircling the burner and depending from the bottom edge of the concavo-convex portion 5 is a shield 8 that acts to deflect the heat from the burners. Arranged across the flues 3, 3 respectively at the lower ends thereof are air dampers 9 pivoted within the respective flues for swinging movement and connected with chains 10 that extend upwardly in the flues and have the upper ends thereof trained over the upper edges of the flues so that the chains may be operated to open and close the dampers so as to vary the quantity of air passing through the flues.

The burner 6 is of any suitable construction and is equipped with a controlling valve 11 connected through the medium of suitable gearing 12 with the lower end of a vertical shaft 13 arranged in one of the flues 3 and having the upper end thereof terminating adjacent to the upper end of the flue so that the shaft may be rotated to open and close the valve.

14 designates a supply tank located in some suitable position and connected by 100 means of a pipe line 15 with the burner 6, the pipe line extending down through one of the flues 3.

The concavo-convex portion 5 of the top wall of the casing 1 is preferably lined with asbestos 16 and is formed with vent holes from which lead vent pipes 17 extending upwardly from the casing and terminating above the water line of the tank in which the heater is arranged.

In practice, the heater is placed in the tank containing the water or other liquid to be heated and the burner set in operation and in the operation of the burner cold air is drawn downwardly through the flues 3 and the products of combustion escape through the vent pipes 17 and in this circulation of the air the water in contact with the flues, the casing and the vent pipes is heated and owing to the arrangement of the 110

flues and the vent pipes the water may circulate between the same so as to expedite the heating of the water in the tank.

While we have herein shown and described the preferred form of our invention by way of illustration, we wish it to be understood that we do not limit or confine ourselves to the precise details of construction herein described and delineated, as 10 modification and variation may be made within the scope of the claim and without departing from the spirit of the invention.

We claim:

15 A heater adapted to be submerged in a tank of water or other fluid to be heated comprising a casing, air flues extending upwardly from the casing at the respective ends thereof and terminating above the water line, the central portion of the top wall

of the casing between said flues being concavo-convex, a burner in said casing below said concavo-convex portion, pipes leading upwardly from said concavo-convex portion, an asbestos lining for said concavo-convex portion, a grate interposed between 25 said burner and said concavo-convex portion of said casing to break up the flame from the burner, and means extending upwardly through one of said air flues for regulating said burner.

In testimony whereof we affix our signatures in presence of two witnesses.

WARREN T. HEAPS.
WILLIAM THACKERAY.
